UNITED STATES PATENT OFFICE.

FREDOLF J. PETERSON, OF SALEM, OHIO.

ADDING ATTACHMENT FOR CREDIT-REGISTERS.

1,151,123.

Specification of Letters Patent.

Patented Aug. 24, 1915.

Application filed October 28, 1913. Serial No. 797,762.

To all whom it may concern:

Be it known that I, FREDOLF J. PETERSON, a citizen of the United States, residing at Salem, in the county of Columbiana and State of Ohio, have invented a new and useful Improvement in Adding Attachments for Credit-Registers, of which the following is a specification.

My invention relates to improvements in adding attachment for credit registers in which an adding machine is employed in connection with a credit register whereby a credit register especially of the leaf type can be used in the ordinary way when the adding attachment is constructed.

The objects of the present invention are, first, to provide an attachment whereby the total amount of credits extended for a definite time, as for instance a day's business can be determined; second, to so connect the adding device that at the time a single credit can be added; and third, so arrange the adding attachment that it can be easily operated and the accurate total credit extended easily, accurately and quickly determined.

These objects, together with other objects readily apparent to those skilled in the art, I attain by the construction illustrated in the accompanying drawings, although my invention may be embodied in a variety of other mechanical forms, the construction illustrated being chosen by way of example.

In the accompanying drawings, Figure 1 is a perspective view of the adding attachment. Fig. 2 is a top view partially in horizontal section, the casing or cover being removed. Fig. 3 is a section on line 3-3, Fig. 2, looking to the left. Fig. 4 is a section on line 4-4, Fig. 2, looking to the right.

Fig. 5 is a perspective view of a credit register of the leaf type showing the adding device in proper relative relationship therewith and connected. Fig. 6 is a top view showing the top edge of a portion of the front leaf of a credit register, also showing the proper relative arrangements of the actuating bars and adding device. Fig. 7 is a vertical section of the adding device showing one set of the actuating levers and their different parts in condition for engagement and one of such parts in dotted lines in their normal position. Fig. 8 is a section showing a portion of one of the computing disks and pick up fingers showing said pick up fingers properly attached.

Similar numerals of reference indicate

corresponding parts in all the figures of the drawing.

In the accompanying drawing, 1 represents the outer casing or cover of the adding attachment which is substantially of the form shown and should be formed of such a size that it can be properly connected to the desk portion 2 of the credit register cabinet 3. To the end members of the inner 60 casing 1^a is attached the bar 4, which bar is provided with the key-way 5. Upon the bar 4 are fixedly mounted the hubs 6 of the disks 7, said hubs and disks 6 and 7 being preferably formed integral, and are held against 70 rotation by means of the keys 8.

Upon the bar 4 are independently and loosely mounted the combined computing and toothed disks 9 and 10, each one of said disks 9 and 10 being preferably formed integral with each other, but may be made separate and attached together in any convenient and well known manner, as the only object is to provide means whereby by the rotation of the toothed disks the computing 80 disks will rotate or move therewith. Upon the peripheries of the computing disks are located figures 0 to 9 inclusive, and for the purpose of compactness the periphery of each computing disk may be provided with 85 a series of figures from 0 to 9 inclusive, each set of figures occupying a portion of the peripheries of the computing disks.

In the drawings each set of figures is so arranged that they will occupy substantially 90 one-fourth of the entire periphery or in other words four series or sets of complete numerals from 0 to 9 inclusive are designed to be located upon each periphery of the various computing disks 9; but it will be understood that this arrangement can be varied 95 without departing from the nature of the invention.

At the rear of the various disks is located a bar 11, which bar is fixed to the end members of the casing 1^a and is for the purpose of providing means for pivotally connecting the rear members or sections 12, which constitute portions of the computing disk actuating keys. To the front or forward ends 100 of the members 12 are pivotally attached the front or forward members of the keys 13 and to the top or upper ends of the forward members 13 are attached the pointed teeth engaging fingers or bars 14, to which bars are attached the caps or knobs 15. It will 105 be understood that the caps or knobs 15

may be attached in any equivalent mechanical manner as the only object desired to be accomplished is to so attach the caps or knobs that they will be in proper position 5 to manipulate the various keys.

For the purpose of providing means for moving the forward members 13 of the keys to or from the toothed disks 10 the key sections 12 and 13 are pivoted together by 10 means of rivets 16 and for the purpose of making what might be termed a break joint the members 12 are provided with the lips 17, which lips limit the pivotal movements of the key members 13 in one direction.

15 To the housing or inclosing frame 1^a is attached the top or upper end or portion of the front slotted and curved cover 19, the bottom or lower end of said slotted cover being attached to the bar 20 secured to the 20 casing 1^a. For the purpose of producing a neat and finished appearance the slotted cover 19 should be provided with the downward extending flange 21, through which flange the connecting screws 22 are passed 25 and seated in the bar 20. The cover 19 is provided with a series of slots 23, at the sides of each of the slots 23 are located the figures from 1 to 9 inclusive, and for the purpose of providing means for properly 30 reading the computing disks 9 from time to time the sight recesses or openings 24 located at the top or upper ends of the slots 23 are provided.

In use the computing disks 9 are actuated 35 from time to time by the actuating keys and the toothed disks 10 and in the beginning of the starting of adding up credits the various computing disks are all brought into such a position that the ciphers will be brought in 40 alinement with the sight apertures 24, at which time the adding attachment is in position to commence the day's business or any predetermined period of business. These various computing disks are set by means of 45 the keys as follows: The caps or knobs 15 are grasped by the hand of the operator and the teeth engaging fingers or bars 14 set in the teeth of the toothed disks 10 and moved downward by means of the caps or knobs 50 the desired distance.

For the purpose of limiting the downward movements of the keys together with their different attachments the flanges or forward extensions 25 of the teeth engaging fingers 55 or bars 14 are formed of such a size that they will rest upon the upper face of the horizontal flange 26, or its equivalent.

After the adding attachment has been 60 properly set for use the various keys designed to actuate the computing scales are manipulated substantially as follows: Assuming that the credit designed to be given amounts to \$9.57 the first right hand key is placed in the position illustrated in Fig. 1 65 after which the keys are brought down to

their lowermost points and the credit would read on the computing disks \$9.57, said figures appearing under the sight apertures 24. These various keys may be manipulated separately or together as desired. In case further credit is desired to be given, the various keys are set and afterward pressed down. In Fig. 1 one of the keys is shown extended and ready to be brought into proper engagement with the toothed disk 10 directly under 75 said key.

It will be understood that some means must be provided for picking up the various computing disks from time to time and in order to provide for thus picking up the 80 disks the side faces of the computing disks are provided with the transfer pawls 27, which transfer pawls are pivotally attached by means of the ears 28 and for the purpose of holding said transfer pawls 27 out of engagement with the teeth of the toothed disks 10 except at such times as it is desired to have said pawls engage one of the teeth of the toothed disks, the fixed disks 7 are provided, which fixed disks hold the fingers 27 85 up and away from the teeth.

For the purpose of permitting the transfer pawls to engage the proper tooth the disks 7 are provided with the notches or recesses 29 into which recesses the transfer 95 pawls are permitted to drop a sufficient distance to engage the proper tooth. For the purpose of insuring the proper dropping of the transfer pawls 27 the springs 30 are provided, which springs are connected to the 100 casing 1^a and are so arranged that they will press or bear against the top or upper edges of the pawls 27 and press the transfer pawls downward and into proper engagement with the proper toothed wheel or disk 10.

The notches 29 should be provided with inclined edges so that as the computing disks move the transfer pawls will gradually drop or ride down the inclined edge, and then up the opposite incline and on to the peripheries of the fixed disk 7. It will also be understood that some provision should be made to prevent the transfer pawls from dropping or turning on their pivotal points other than above described, and in order to prevent the dropping or turning on their pivotal points, other than above described, and in order to prevent the dropping as they pass around and under the disks 7 the pivoted ends of the transfer pawls are formed 110 square for a portion of their width, which square portion abuts against the faces of the computing disks 9.

It will be understood that there should be no backward movement of the various computing disks and in order to prevent this backward movement the springs 31 are provided, which springs are connected to the casing 1^a and extend forward and engage the ratchet teeth of the toothed disks 10. It 115 120 125 130

will also be understood that the hubs 6 should be formed of such a width that the various disks and wheels mounted upon the shaft or bar 4 will be properly spaced, said 5 hubs acting as spacing thimbles. For the purpose of properly spacing the key members 12 upon the bar 11, suitable spacing thimbles 32^a are provided, which thimbles may be loosely mounted upon said bar as 10 their only purpose is to provide suitable means for properly spacing the key members 11.

To the credit account cabinet is pivotally attached the lever 32, which lever extends 15 downward below the pivotal point of the front or forward leaf 33 and is extended upward above the pivotal point so that when the front leaf 33 is moved into a horizontal position the bottom or lower end of the lever 20 32 will be moved rearward with reference to the adding attachment proper at which time the bar 34 will be moved rearward, said bar being pivotally connected to the bottom or lower end of the lever 32. To the front or 25 forward end of the bar 34 is attached the cross bolt 35, which cross bolt is formed of sufficient length to attach the connecting links 36, the number of said links corresponding with the number of computing 30 disks 9, and the number of actuating keys.

The front or forward ends of the connecting links 35 are pivotally connected to the key members 12 and are so connected for the purpose hereinafter described. By providing the bar 34 and the connecting links 35 it will be understood that when the front leaf 33 is brought down into a horizontal position by itself or with any number of leaves of the series of leaves in the credit 35 40 cabinet the various computing disk keys will be brought down to their lowermost point providing they have been previously set as illustrated in Fig. 1 or in any other position thereby properly registering the amount of credit designed to be given when the front leaf 33 is brought into a lowered or horizontal position.

For the purpose of allowing the computing disk keys to be actuated independent of the credit leaves or regardless of the position of said leaves the connecting links 36 are provided with the elongated slots 37 through which elongated slots the connecting bolt 35 is passed, and for the purpose of preventing any end pull of the bolt 35 the bracket arm 38 is provided, which bracket arm is attached in any convenient and well known manner to the bar 34 and its opposite or forward end connected to the connecting bolt 35, by which arrangement an even pull is given to both ends of the connecting bolt 35.

It will be understood that before the connecting links 36 are moved or pulled endwise the bolt 35 must be brought to the rear

end of the elongated slots 37 at which time the bar 34 and the links 36 move in unison. It will be understood that when the members 13 of the computing disk actuating keys are not brought to their full height, the connecting links 36 will not be brought forward to their full limit, so all of the keys that have been set up, regardless of their relative position will be picked up when the bar or bolt 35 comes in contact with the rear ends 70 75 of the elongated slots 37. It will also be understood that by providing the elongated slots 37 the keys can be actuated independent of the credit account leaves, owing to the fact that as the connecting links 36 are 80 moved backward by the downward pressure of any given key to actuate a given computing disk the connecting links 36 slide upon the bolt 35 without imparting any movement whatsoever to the bar 34.

For the purpose of assisting in bringing the credit account leaves contained in a credit account register into their vertical positions the credit account cabinet proper is provided with the ordinary and common 90 lever 32^a, which is constructed and arranged in the usual manner and does not have to do with the present invention, hence no detailed description is deemed necessary as such a structure is common and well known in the 95 art.

The lever 32 being pivoted intermediate its ends will be actuated when in the position illustrated in Fig. 7 by the downward movement of the front or forward leaf 33, 100 but will not be actuated when the leaves are brought into their vertical position, but when any given computing disk key is moved upward or set for engagement with any particular toothed wheel or disk 10, 105 said lever will be actuated in the opposite direction from the direction it is actuated by the downward movement of the front or forward leaf 33, it being understood that the lever 32 will not be actuated to its full limit 110 unless a certain key or any particular key is moved upward to its extreme limit, but regardless of the position of the lever or rock bar 32 its bottom or lower end will be brought backward to its full limit when the 115 leaves are brought into a horizontal position. In other words the lever or rock arm 32 may not be in position to be actuated until after the front or forward leaf has been partially lowered or until it comes in contact with the upper free end of said lever or rock arm 32.

Having fully described my invention what I claim as new and desire to secure by Letters Patent, is—

1. In an adding machine of the character described, the combination of a casing, a shaft fixed to and carried by said casing, a series of toothed computing wheels loosely mounted upon said shaft, the periphery of 120 125 130

each wheel being provided with a plurality of series of figures from 0 to 9, a cover provided with slots, said cover also provided with figures near the edges of said slots, a series of partitions located between said wheels, each of said partitions provided with a recess, a series of transfer pawls connected to the computing wheels, a series of springs adapted to actuate the transfer pawls, a shaft carried by said casing and located in the rear of said disks, a series of keys pivoted to said shaft, said keys being pivoted intermediate their ends, means for limiting the pivotal movement in one direction, said keys provided with teeth engaging fingers, said fingers adapted to actuate the toothed computing wheels, and finger buttons provided upon the free ends of said keys.

2. In an adding machine of the character described, the combination of a casing, a shaft fixed to and carried by said casing, a series of toothed computing wheels loosely mounted upon said shaft, the periphery of each of said computing wheels being provided with a plurality of series of figures from 0 to 9, a cover provided with slots, said cover also provided with figures near

the edges of said slots, a series of disks located between said computing wheels and fixedly mounted upon said shaft, each of said disks provided with a recess in its periphery, a plurality of transfer pawls carried by the computing wheels, one of said pawls being provided for each series of numbers from 0 to 9 upon each computing wheel, said transfer pawls adapted to travel around the periphery of said disks, springs adapted to throw said pawls into said recesses, a shaft carried by said casing and located in the rear of said disks, a series of keys pivoted to said shaft, said keys being pivoted intermediate their ends, means for limiting the pivotal movement in one direction, said keys provided with teeth engaging fingers and said fingers adapted to actuate the toothed computing wheels, and finger buttons provided upon the free ends of said keys.

In testimony that I claim the above, I have hereunto subscribed my name in the presence of two witnesses.

FREDOLF J. PETERSON.
